US00D578142S

(12) **United States Design Patent**
Ewringmann

(10) **Patent No.:** **US D578,142 S**
(45) **Date of Patent:** **** Oct. 7, 2008**

(54) **ROAD CONSTRUCTION MACHINE**

(75) Inventor: **Ulrich Ewringmann,**
Taufkirchen-Potzham (DE)

(73) Assignee: **Joseph Voegele AG**, Mannheim (DE)

(**) Term: **14 Years**

(21) Appl. No.: **29/269,038**

(22) Filed: **Nov. 16, 2006**

(30) **Foreign Application Priority Data**

May 16, 2006 (EM) 000539432

(51) **LOC (8) Cl.** **15-03**

(52) **U.S. Cl.** **D15/22**

(58) **Field of Classification Search** D15/10,
D15/13, 19, 22-26; 404/75, 108, 101, 102,
404/110, 118, 84.05

(57) **CLAIM**

The ornamental design for a road construction machine, as shown and described.

DESCRIPTION

FIG. 1 is a perspective view of a first embodiment of my road construction machine showing my new design in an open hopper configuration, the bottom surface being devoid of surface ornamentation;

FIG. 2 is a left elevation view of the road construction machine of FIG. 1;

FIG. 3 is a front elevation view of the road construction machine of FIG. 1;

FIG. 4 is a right elevation view of the road construction machine of FIG. 1;

FIG. 5 is a rear elevation view of the road construction machine of FIG. 1;

FIG. 6 is a top plan view of the road construction machine of FIG. 1.

FIG. 7 is a perspective view of a second embodiment of my road construction machine showing my new design in a closed hopper configuration, the bottom surface being devoid of surface ornamentation;

FIG. 8 is a left elevation view of the road construction machine of FIG. 7;

FIG. 9 is a front elevation view of the road construction machine of FIG. 7;

FIG. 10 is a right elevation view of the road construction machine of FIG. 7;

FIG. 11 is a rear elevation view of the road construction machine of FIG. 7; and,

FIG. 12 is a top plan view of the road construction machine of FIG. 7.
